United States Patent Office.

GEORGE L. WATSON, OF NESQUEHONING, PENNSYLVANIA.

Letters Patent No. 98,132, dated December 21, 1869.

IMPROVEMENT IN GAUGE-COCKS.

The Schedule referred to in these Letters Patent and making part of the same.

To all whom it may concern:

Be it known that I, GEORGE L. WATSON, of Nesquehoning, in the county of Carbon, and State of Pennsylvania, have invented certain Improvements in Gauge-Cocks for Steam-Boilers, of which the following is a specification.

Nature and Objects of the Invention.

The first part of my invention relates to the combination of a cap provided with a stop-screw, and a gauge-cock stem, fitted with a stop-cock, and provided with a screw and a projecting seating; the object of this part of my invention being to permit of cleaning the gauge-cock stem when it becomes obstructed, and of repairing the seating, when it may be necessary, without blowing the steam and water from the boiler.

The second part of my invention relates to the combination of a cap provided with a hollow stop-cock, and a gauge-cock stem, fitted with a stop-cock, and provided with a projecting screw; the object of this part of my invention being substantially the same as that of the first part. It is also intended as a substitute for the cap used in the first part of the invention, and is to be substituted and used after the seating of the gauge-cock stem has become so worn, from repeated repairs, as to be ineffectual for the purpose for which it was intended.

Description of the Drawings.

Figure 1 is a longitudinal section of a gauge-cock, embodying the first part of my invention.

Figure 2 is a detached view of a cap with a stop-screw.

Figure 3 is a partial sectional view of a gauge-cock, embodying the second part of my invention.

Figure 4 is a detached view of the cap with the hollow stop-cock.

General Description.

a is a gauge-cock stem.

b is a stop-cock, fitted in the same.

c is a cap, which is screwed over the end of the gauge-cock stem *a*.

d is a stop-screw, used with the cap *c*.

e e is the seating of the gauge-cock stem *a*.

The point of the screw *d* meets the seating *e e*, thereby closing the opening *f* in the gauge-cock stem *a*.

g is a cap, provided with a hollow stop-cock, *h*, which is screwed over the end of the gauge-cock stem *a*, and is used in the second part of my invention.

Operation of the Invention.

The gauge-cock stem *a*, fitted with the stop-cock *b*,

and provided with the seating *e e*, and the cap *c*, provided with the stop-screw *d*, operated in combination, compose the first part of my invention.

The stop-cock *b* is usually left open.

When it becomes necessary to clean the gauge-cock stem *a*, or to repair the seating *e e*, the stop-cock *b* must be turned so as to shut off the steam and water. The cap *c* may then be removed, which enables one to get at the opening *f* in the gauge-cock stem *a*, or at the seating *e e*.

If the opening *f* be obstructed, the stop-cock *b* may be turned open, and the obstruction removed by running a wire through the opening *f*.

As soon as the steam escapes, or the water flows, the stop-cock *b* can be closed.

By shutting off the steam and water with the stop-cock *b*, and removing the cap *c*, the seating *e e* can be repaired at any time.

The seating *e e* is so constructed that it will admit of repeated repairs, as also is the point of the screw *d*. Either of them can be repaired, until they are worn to the threads of the screws from which they project.

When the seating *e e*, and the point of the screw *d* can no longer be repaired, the cap *c* may be discarded and the cap *g*, provided with the hollow stop-cock *h*, may be substituted in its stead.

The cap *g*, provided with the hollow stop-cock *h*, and the gauge-cock stem *a*, fitted with the stop-cock *b*, operated in combination, compose the second part of my invention.

The gauge-cock stem *a* may be cleaned in the same manner as in the first part of my invention, when the cap *c* is used.

Claims.

I claim, as my invention—

1. The gauge-cock stem *a*, provided with the stop-cock *b*, and having a projecting seating, *e e*, adapted for use in connection with the cap *c* and stop-screw *d*, in the manner and for the purpose specified,

2. The cap *g*, provided with the hollow stop-cock *h*, when said cap is adapted for use upon the gauge-cock stem *a*, fitted with the stop-cock *b*, with or without the seating *e e*, all in the manner and for the purpose specified.

In testimony that I claim the foregoing improvement in gauge-cocks for steam-boilers, as above described, I have hereunto set my hand and seal, this 23d day of September, 1869.

GEORGE L. WATSON. [L. S.]
